UNITED STATES PATENT OFFICE.

JAY H. SWIFT, OF PHILADELPHIA, PENNSYLVANIA.

BAND FOR ENGAGING AND HOLDING THE ENDS OF THE RIBS OF UMBRELLAS WHEN CLOSED.

1,425,806.

Specification of Letters Patent. Patented Aug. 15, 1922.

Application filed August 3, 1921. Serial No. 489,629.

To all whom it may concern:

Be it known that I, JAY H. SWIFT, a citizen of the United States, residing at 734 Shirley Street, Philadelphia, in the county 5 of Philadelphia and State of Pennsylvania, have invented a new and useful Band for Engaging and Holding the Ends of Ribs of Umbrellas When Closed, of which the following is a specification.

10 My invention consists of an appliance which I preferably make of a strip of flat spring steel wound fast on a mandril, to form a flat band of one or two turns.

15 The object of my invention is so to make and construct a band that can be applied to the handle of any umbrella, and to adjust itself automatically to any sized handle, which will clasp the handle and remain in that position when the umbrella is raised.

20 I also wish to make a band that can be adjusted and operated by any one using it.

I attain these objects by the mechanism illustrated in the accompanying drawings in which—

25 Fig. 1 illustrates the band on the handle of umbrella.

Fig. 2 illustrates the band holding the ends of the ribs of umbrella when closed.

30 Fig. 3 illustrates the band when disengaged from umbrella.

A shows construction of the band.

B shows the free inside end of the flat coil.

C shows the free outside of the flat coil, with end turned out, in order that it can 35 slide freely over rod of umbrella.

The ends must be free to allow the band to pass over the rod of umbrella.

The object of my invention is not to hold umbrella in a tight roll, but to hold the ends 40 of ribs together.

The way my invention is to be operated is as follows:

The band is passed over the rod of umbrella, and pushed up over the handle; the 45 tension of the spring in the steel holds it on the handle. To engage the ends of the ribs, push the band down over them, and when the umbrella is to be opened, push the band back on the handle. 50

I claim—

As an article of manufacture, a band adapted to hold the ribs of an umbrella when closed, comprising a narrow elongated band of resilient material formed in 55 a coil, the turns of the coil being spaced apart, and lying in the same plane, the outer terminal of the coil being flared outwardly.

J. H. SWIFT.
